CLAIM

We claim the ornamental design for a hair shaver, as shown and described.

DESCRIPTION

FIG. 1 is a front perspective view from above of an embodiment of the claimed design;

FIG. 2 is a rear perspective view from below of the claimed design of FIG. 1;

FIG. 3 is a top view of the claimed design of FIG. 1;

FIG. 4 is a bottom view of the claimed design of FIG. 1;

FIG. 5 is a right side view of the claimed design of FIG. 1;

FIG. 6 is a left side view of the claimed design of FIG. 1;

FIG. 7 is a front view of the claimed design of FIG. 1;

FIG. 8 is a rear view of the claimed design of FIG. 1;

FIG. 9 is a front perspective view from above of another embodiment of the claimed design;

FIG. 10 is a rear perspective view from below of the claimed design of FIG. 9;

FIG. 11 is a top view of the claimed design of FIG. 9;

FIG. 12 is a bottom view of the claimed design of FIG. 9;

FIG. 13 is a right side view of the claimed design of FIG. 9;

FIG. 14 is a left side view of the claimed design of FIG. 9;

FIG. 15 is a front view of the claimed design of FIG. 9; and,

FIG. 16 is a rear view of the claimed design of FIG. 9.

The ornamental design which is claimed is shown in solid lines in the drawings. The broken lines shown in the drawings illustrate portions of the hair shaver and form no part of the claimed design.

1 Claim, 14 Drawing Sheets
